(74) **Attorney, Agent, or Firm:** John H. Choi & Associates

(57) **CLAIM**

The ornamental design for a multi-purpose grooming device, as shown and described.

DESCRIPTION

FIG. 1 is a perspective view of an embodiment of the multi-purpose grooming device showing my new design; FIG. 2 is a front plan view of the multi-purpose grooming device of FIG. 1;

FIG. 3 is a rear plan view of the multi-purpose grooming device of FIG. 1;

FIG. 4 is a left side view of the multi-purpose grooming device of FIG. 1, with the right side view being a mirror image of the left side view;

FIG. 5 is a top plan view of the multi-purpose grooming device of FIG. 1;

FIG. 6 is a bottom plan view of the multi-purpose grooming device of FIG. 1;

FIG. 7 is FIG. 2 with a front upper grip detailed;

FIG. 8 is an enlarged view of the front upper grip of FIG. 7;

FIG. 9 is FIG. 3 with a rear upper grip detailed;

FIG. 10 is an enlarged view of the rear upper grip of FIG. 9;

FIG. 11 is FIG. 4 with a left intermediate grip detailed, a right intermediate grip on the right side being a mirror image of the left intermediate grip; and,

FIG. 12 is an enlarged view of the left intermediate grip of FIG. 11.

EX PARTE
REEXAMINATION CERTIFICATE

THE PATENT IS HEREBY AMENDED AS 5
INDICATED BELOW.

Matter enclosed in heavy brackets [ ] appeared in the
patent, but has been deleted and is no longer a part of the
patent; matter printed in italics indicates additions made
to the patent. 10

ONLY THOSE PARAGRAPHS OF THE
SPECIFICATION AFFECTED BY AMENDMENT
ARE PRINTED HEREIN. 15

In the DESCRIPTION:

*The knurled surface on the top one-third portion of the rat
tail shown in FIGS. 1-4, 7, 9 and 11 is part of the claimed* 20
design.

THE DRAWING FIGURES HAVE BEEN
CHANGED AS FOLLOWS:

FIG. Nos. 1, 4, 8, 10, 11. 25
Figures corrected for consistency.

AS A RESULT OF REEXAMINATION, IT HAS BEEN
DETERMINED THAT: 30

The patentability of the claim is confirmed.
